UNITED STATES PATENT OFFICE

129,701

DESIGN FOR A BOLT RACK

William Daines, Jr. and Howard E. Makin,
Logan, Utah

Application July 8, 1941, Serial No. 101,960

Term of patent 14 years

To all whom it may concern:

Be it known that we, William Daines, Jr., and Howard E. Makin, citizens of the United States, residing at Logan, in the county of Cache and State of Utah, have invented a new, original, and ornamental Design for a Bolt Rack, of which the following is a specification, reference being had to the accompanying drawing, forming part thereof.

Figure 1 is a top plan view of a bolt rack, showing our new design.

Figure 2 is a side elevational view thereof.

Figure 3 is an end elevational view.

We claim:

The ornamental design for a bolt rack, as shown.

WILLIAM DAINES, JR.
HOWARD E. MAKIN.
